UNITED STATES PATENT OFFICE

JOHN KING RECKFORD, OF NEW YORK, N. Y., ASSIGNOR TO AMERICAN LEAD PENCIL COMPANY, OF NEW YORK, N. Y., A CORPORATION OF NEW YORK

DISPLAY RACK

Application filed May 25, 1928. Serial No. 280,437.

This invention relates to display racks and more particularly racks for holding and displaying pen holders, pencils, etc.

The present invention contemplates a display rack of this character made from suitable sheet material, such for example as cardboard, adapted to be supported on an easel or suspended from a suitable support. On such display racks it is desirable to present a unique and attractive form for supporting and displaying the articles and at the same time to provide a suitable surface on the body of the rack for carrying desired advertising or descriptive matter, which will be visible when the articles being displayed are positioned in the rack, at the same time keeping the size of the rack down to a minimum, in order to reduce the cost of the rack and also in order to conserve space consumed by the rack.

With this and other objects in mind, an object of the present invention is to provide a device of the character described which may be produced economically and efficiently and which will obtain the advantages above set forth.

Further and more specific objects, features and advantages will more clearly appear from the detailed description given below, taken in connection with the accompanying drawings which form a part of this specification.

In the accompanying drawings:

Fig. 1 is a plan view of a preferred embodiment of the rack made from a single piece of sheet material, such as cardboard, suitably scored or cut with the scored portions of the rack still remaining in the plane of the sheet, and

Fig. 2 is a perspective view of the rack with the scored portions bent outwardly and in which the articles to be displayed are indicated in dash lines.

The sheet of cardboard is indicated as 1 and having a suitable means for supporting the same adjacent its top edge provided by the hole 2. An elongated flap 3 is formed by cutting or scoring the cardboard along the line 4, and the flap 3 is adapted to be bent about the line 5 to form a hinge connecting the flap to the sheet 1. The flap 3 is provided

with a plurality of holes 6 providing a series of holes extending longitudinally of the flap 3. Said holes are formed with serrated peripheries, providing thereby yieldable friction engaging means for firmly holding the articles inserted in said holes. Spaced laterally from flap 3 is a similar flap 3', corresponding in all details of construction with flap 3 and in longitudinal alignment with flap 3. Spaced downwardly beneath flap 3 the sheet 1 is cut or scored by line 7, to thereby form flap 8 which is adapted to be bent outwardly beneath flap 3 about the line 9 as a hinge. The flap 8 is provided with a longitudinal slot 10 so formed as to fall in substantial vertical alignment with the series of holes 6 in flap 3 and being of a width substantially less than the diameter of the holes 6. The flap 8 has its outer edge positioned substantially beneath the outer edge of flap 3 and is much shorter in length laterally, and might therefore be said to lie in offset position with respect to flap 3.

A flap 8' is positioned beneath flap 3' corresponding respectively to the position of flap 8 with respect to flap 3, and is formed in all respects in accordance with flap 8 herefore described.

In Fig. 2 the flaps 3, 3', 8 and 8' are bent outwardly, the upper flaps about their lower hinged edge, and the lower flaps around their upper hinged edge; thereby providing supporting means for articles such as the pen holders 11. The pen holders 11 are inserted respectively in the individual holes 6, 6' and due to the serrated periphery of said holes the pen holders are firmly gripped therein, with the lower staff of the pen holders extending downwardly and passing through the respective slots 10, 10' in the lower flaps 8 and 8'. The flaps 3 and 3' being hingedly connected at their lower edge provide a supporting shelf for the pen holders, which are grasped therein by means of the serrated peripheral edges of the holes 6, 6'; and the lower flaps 8, 8' being hingedly connected at their upper edge tend to bend downwardly, thereby gripping the lower end of the pen holders therein.

It will be readily seen and appreciated

from the accompanying drawings that by arranging the supporting flaps in the manner above described a maximum area, indicated by the dash lines and designated as 12, is provided for suitable advertising or descriptive printing on the card; and such area is visible at all times even when all of the pen holders 11 are positioned in the display rack. This is considered of great importance, since in display racks of this kind it is desirable to have as much space available for such advertising or descriptive printing, and at the same time permitting the same to be viewed while the display rack is full of articles. By the present invention I have provided for this maximum of free area, at the same time keeping the size of the rack to a minimum and in addition providing an efficient supporting and displaying structure which lends itself to economic and rapid production.

Having thus described my invention with particularity with reference to its preferred form, it will be obvious to those skilled in the art, after understanding my invention, that various changes and modifications may be made therein without departing from the spirit and scope of my invention, and I aim in the appended claims to cover such changes and modifications as are within the scope of the invention.

What I claim is:

1. As an article of manufacture, a display rack made of sheet material and comprising an upper integral flap hingedly attached along one edge and provided with a series of holes, a lower integral flap hingedly attached along one edge and provided with an elongated hole extending lengthwise thereof and positioned in substantial vertical alignment beneath the said series of holes of the upper flap when said flaps are bent outwardly, said lower flap being of substantially less length than said upper flap and being offset with respect thereto and having one end in substantial alignment with one end of said upper flap, and a similar series of flaps formed in said card in laterally disposed relation to said first series of flaps thereby providing a maximum printing area between said flaps free from obstruction by articles displayed in said rack.

2. As an article of manufacture, a display rack made of sheet material and comprising a series of upper and lower spaced apertured integral supporting flaps to support groups of elongated articles such as pencils and pen-holders, said flaps constructed and arranged so that the articles of one group are supported thereon in a downward and outward direction with respect to the articles in the other group to expose a central area on the sheet for printed and advertising matter.

3. As an article of manufacture, a display rack comprising a flat sheet of cardboard,

two pairs of upper and lower integral spaced apertured flaps disposed on opposite side of the vertical middle line of the sheet, the flaps arranged to support the articles in a downwardly divergent manner to leave a central exposed area on the sheet for printed and advertising matter.

4. As an article of manufacture, a display rack made of sheet material comprising an integral flap having a series of apertures therein to receive articles to be supported, a lower integral flap having a slot therein to receive and guide the lower ends of the articles and disposed in an offset manner with respect to the upper flap so as to swing the lower ends of the articles to one side of the vertical.

5. As an article of manufacture, a display rack made of sheet material comprising an integral flap having a series of apertures therein, the edges of the apertures being serrated to increase the grip on the supported articles, a lower integral flap thereon having a slot therein merely to receive and guide the lower ends of the supported articles, said lower flap disposed in an offset manner with respect to the upper flap so as to swing the lower ends of the articles to one side of the vertical whereby a central area of the sheet is exposed for use for printing and advertising matter.

In testimony whereof I have signed my name to this specification.

JOHN KING RECKFORD.
